UNITED STATES PATENT OFFICE.

EUGENE W. HAWLEY, OF PHILADELPHIA, PENNSYLVANIA.

RETAINING DEVICE FOR GARMENT RETAINERS.

1,413,659.

Specification of Letters Patent. Patented Apr. 25, 1922.

Application filed June 2, 1921. Serial No. 474,364.

To all whom it may concern:

Be it known that I, EUGENE W. HAWLEY, a citizen of the United States, residing at Philadelphia, county of Philadelphia and 5 State of Pennsylvania, have invented a new and useful Improvement in Retaining Devices for Garment Retainers, of which the following is a full, clear, and exact description, reference being had to the accompanying 10 drawings, which form a part of this specification.

My invention relates to an improved device by means of which garments hung in the garment or hanger compartment of a 15 wardrobe trunk will be pressed together and held against the rear wall of the compartment and which will be securely held in any desired adjusted position irrespective of the position in which the trunk is placed or how 20 it may be handled.

My invention has for its object the provision of a device which when the trunk is closed will act to positively retain the garments and when the trunk is open will be 25 readily removable or adjustable, and which will be inexpensive to manufacture and readily manipulated.

A somewhat similar device is disclosed in a patent issued to me July 25, 1916, numbered 1,192,521, and said device is entirely feasible and practical. The present application, however, discloses an improved device which possesses many advantages and for certain purposes is better adapted for 35 use in certain forms of trunks.

Having now indicated in a general way the nature of my invention, I will proceed to describe a preferred embodiment thereof in detail with reference to the accompanying 40 drawings, in which—

Fig. 1 is a perspective view of a wardrobe trunk, in open position, embodying my invention.

Fig. 2 is a cross-sectional view of the 45 trunk shown in Fig. 1 showing the embodiment of my wardrobe from above.

Fig. 3 is a sectional view on line 3—3 Figure 2.

Fig. 4 is a sectional view, with the trunk 50 in closed position, showing an elevation of a detail of my device.

The trunk shown comprises a drawer compartment *a*, provided with drawers *b*, to which is hinged a garment or hanger compartment *c* the lid *d* of which is hinged to 55 the back. Secured to the side and adjacent the top of the hanger compartment are rods *e* adapted for the support of clothes hangers *f*. Supporting frames *g* and *h*, of channel section, are secured opposite each other, to 60 the side walls of the compartment *c*, below the hanger supporting rods *e*. The frame *g* is provided in its side with a plurality of slots *i*, while the frame *h* is provided with a plurality of slots *j* which extend through its side and top. A solid cover *k* normally overlying the slots in the top of frame *h* is hinged on the frame and provided at its forward end with an extension *m*. The cover is made somewhat wider 70 than the width of the top of the supporting frame and its edge extends somewhat beyond the edge of the frame.

A garment retainer comprising a frame *n* is secured to a cross piece *o*, which is provided at its ends with tongues *p*, *p'* adapted to be entered in the slots in the supporting frames *g* and *h* to effect the support of the retainer thereby. The cross piece *o* is positioned about midway of the height of the 75 frame *n*, and the tongues *p*, *p'*, are in width somewhat less than the width of the slots in frames *g* and *h*. Thus the retainer may be moved somewhat out of the vertical in any adjusted position in order to accommodate 80 itself to the difference in thickness at the top and bottom of the garments on the hangers.

A lug or stop *q* is secured to one of the 85 drawers *b*, in the drawer compartment of the trunk, in such a position that when the trunk is closed, by bringing the drawer and garment compartments together, the stop will overlie the extension *m* of cover *k*, as shown in Figure 4.

In the operation of the device, assuming the retainer to be out of the trunk and the garment compartment to be packed, the retainer is put in place by inserting the tongue *p* in one of the slots *i* in frame *g*; the retainer is then manipulated to bring tongue *p'* up under the edge of cover *k* which is 95 100

raised and maintained raised by the tongue; the free end of the retainer is then moved backward and the tongue p' inserted into the proper slot j in the frame h which, as 5 has been noted, extends through the top as well as the side of frame h . When the tongue p' has been entered in frame h , the cover again assumes its position overlying the top of the frame and closing the slots 10 in its top.

When the trunk is closed, the stop q overlies the extension m of the cover and it will be obvious that the cover is thereby prevented from raising or being raised to free 15 slots j and the retainer cannot be removed from the supporting frame, no matter what position the trunk is placed in, or how it is handled.

The advantages of my invention will now 20 be obvious and it will be noted that the garment retainer is securely locked when the trunk is closed, while at the same time when the trunk is open no obstacle is placed in the way of its ready removal and replacement. It will be further noted that after 25 the retainer is placed in the supporting frames it will adjust itself out of the vertical to conform to the garments at the top and bottom thereof and press them firmly 30 together against the rear wall of the compartment.

It will be further noted that when the retainer is inserted in any of the slots j of the supporting frame h , the cover k automatically 35 assumes its normal position overlying and closing the portions of the slots j in the top of the frame, and that when the trunk is closed the cover k is automatically locked by the stop q assuming a position 40 over the extension m on cover k . It will also be noted that the operation of the device is entirely automatic and does not involve the use of springs or other devices liable to get out of order.

Having now fully described my invention, 45 what I claim and desire to protect by Letters Patent is:

1. A wardrobe trunk comprising a compartment for garments, a closure therefor, 50 supporting frames oppositely positioned in said compartment, a garment retainer adjustably supported by said frames, a cover extending along and over one of said supporting frames and movable toward and away 55 therefrom in a direction at an angle to the longitudinal direction of extension of said supporting frame to prevent or permit removal of said garment retainer therefrom, and means carried by said closure adapted 60 when said compartment is closed to lock said cover in position to prevent the removal of said retainer.

2. A wardrobe trunk comprising a compartment for garments, a closure therefor, 65 supporting frames oppositely disposed in

said compartment, one of said frames being provided with a plurality of slots in its face, the other being provided with aligning slots in its face and top, a garment retainer provided with oppositely extending 70 tongues adapted to extend into said slots in the faces of said supporting frames, a cover adapted to removably overlie said last mentioned supporting frame and close the slots in the top thereof, and a stop carried by 75 said closure and adapted when said compartment is closed to overlie said cover, lock it in position overlying said supporting frame, and prevent the removal of said retainer. 80

3. A wardrobe trunk comprising two compartments, supporting frames oppositely positioned in one compartment, one frame having a succession of outwardly opening recesses and the other frame having recesses 85 opening outwardly and upwardly, a garment retainer, laterally projecting members on opposite sides thereof one of which is adapted to engage a recess of the first frame by a lateral movement of the retainer and 90 the other of which is adapted to engage a recess of the second frame by moving downwardly into the same, and a cover adapted to extend over the second frame but movable upwardly to allow insertion and withdrawal of the corresponding retainer member, and means carried by the other compartment adapted, when said compartments are brought together to close the trunk, to prevent such lifting of said cover as to allow the withdrawal of the last named retainer member. 95

4. A wardrobe trunk comprising two compartments, supporting frames oppositely positioned in one compartment, one frame having a succession of outwardly opening recesses and the other frame having recesses opening outwardly and upwardly, a garment retainer, laterally projecting members on opposite sides thereof one of which is adapted to engage a recess of the first frame by a lateral movement of the retainer and the other of which is adapted to engage a recess of the second frame by moving downwardly into the same, and a cover plate 110 overlying the second frame and hinged on an axis extending along the top of the rear thereof. 115

5. A wardrobe trunk comprising two compartments, supporting frames oppositely positioned in one compartment, one frame having a succession of outwardly opening recesses and the other frame having recesses opening outwardly and upwardly, a garment retainer, laterally projecting members 120 on opposite sides thereof one of which is adapted to engage a recess of the first frame by a lateral movement of the retainer and the other of which is adapted to engage a recess of the second frame by moving down- 125

wardly into the same, a cover plate overlying the second frame and hinged on an axis extending along the top of the rear thereof, and means carried by the other compartment adapted, when said compartments are brought together to close the trunk, to prevent the cover from swinging up on its axis

to allow the withdrawal of the last named retainer member.

In testimony of which invention, I have 10 hereunto set my hand, at Philadelphia, Pa., on this 28th day of May, 1921.

EUGENE W. HAWLEY.
